UNITED STATES PATENT OFFICE.

THOMAS J. ALLISON, OF TURNERSBURG, NORTH CAROLINA.

IMPROVEMENT IN RIVETING DEVICES.

Specification forming part of Letters Patent No. 125,924, dated April 23, 1872.

Specification describing a new and useful Improvement in Riveting Device, invented by THOMAS J. ALLISON, of Turnersburg, in the county of Iredell and State of North Carolina.

Figure 1 is a side view of my improved device, partly in section, through the line x x , Fig. 2. Fig. 2 is an under-side view of the same.

Similar letters of reference indicate corresponding parts.

My invention has for its object to furnish an improved device for fastening copper rivets to beltings, harness-straps, &c., which shall be simple in construction, convenient in use, and effective in operation, leaving the rivet with a smooth round head; and it consists in the construction and combination of the various parts of the device, as hereinafter more fully described.

A is a short cylinder, upon one side of which is formed, or to it is attached, a tang or handle, a' , to which the hand-piece B is attached.

The cylinder A is perforated longitudinally, as shown in Fig. 1, said hole being a little larger than the body of the rivet, for heading down which the device is to be used. The lower end of the cylinder A is concaved, as shown in Figs. 1 and 2, to give a slightly-convex form to the washer. C is a plunger, which is made of such a size as to work freely in the hole of the cylinder A . The lower end of the plunger C is concaved, as shown in Figs. 1 and 2, to give a convex form to the head of the

rivet. The plunger C should, for convenience, be made somewhat longer than the cylinder A , and should be connected with the handle a' B by a strap, D , or equivalent flexible connection, so that the plunger may always be at hand ready for use.

In using the device, the rivet is put through the leather and the washer placed upon it. The head of the rivet is then placed upon some hard substance, and the lower end of the cylinder is placed upon the washer, the end of the rivet entering the hole in said cylinder. A blow upon the upper end of the cylinder A drives the washer down snugly upon the leather and draws the head of the rivet even and smooth. The plunger C is then inserted in the cylinder A , and a blow upon its upper end heads down the rivet evenly and smoothly.

Having thus described my invention, I claim as new and desire to secure by Letters Patent—

The combination of the cylinder A , perforated longitudinally and provided with a handle, a' B , the plunger C , and flexible connection D , said cylinder and plunger being constructed and operating in connection with each other, substantially as herein shown and described, and for the purpose set forth.

THOMAS J. ALLISON.
